UNITED STATES PATENT OFFICE

FREDERICK B. WALTER, OF WABASH, INDIANA, ASSIGNOR TO B. WALTER & COMPANY, INC., OF WABASH, INDIANA, A CORPORATION OF INDIANA

HINGE

Application filed July 30, 1928. Serial No. 296,351.

In that type of extension tables wherein an extension leaf may be stored beneath the main top sections, it is common to make the extension leaf in two sections hinged together 5 and having a combined length equal to the width of the table top. In such a construction it has been found difficult to maintain the adjacent ends of the two hinged sections in the same plane when the sections are extended and subjected to a load.

The object of my invention is to produce a sheet metal hinge of cheap but effective form and of such character as to insure proper alinement of the adjacent edges of the hinged 15 leaf sections when said sections are extended.

The accompanying drawings illustrate my invention.

Fig. 1 is an end elevation of my improved hinge in leaf-folding position, with portions 20 of the leaves shown in section;

Fig. 2, a similar view in open position;

Fig. 3, a side elevation of the opened hinge with a leaf section in transverse section;

Fig. 4 a fragmentary under plan of one side 25 of the hinge and adjacent leaf-sections;

Fig. 5 a fragmentary top plan, in partial section of one end of the hinge; and

Fig. 6 a section on line 6—6 of Fig. 5.

In the drawings 10, 10 indicate identical 30 strips of metal of desired length with its ends turned up to form ears 11 and 12 of equal length. Ear 11 is perforated at two points 13, 13 and ear 12 is similarly perforated at 15, 15 but the metal immediately 35 around these perforations is struck up to form bosses 16, 16 of a height equal to the thickness of the connecting levers, to be described. At one side edge ear 11 is provided with a notch 17 and the corresponding side edge of ear 12 is provided with a tongue 18 so formed and placed as to wedge tightly 40 into the notch 17 of a companion strip.

Two strips 10, 10 reversed with relation 45 to each other so that ear 11 of one lies adjacent an ear 12 of the other, are connected at each end by two pairs of L shaped levers 20, 21 and 20, 21. The toes of one lever 20 and one lever 21 are pivotally riveted to the outer face of each ear 11 with their shanks 50 inclined toward the companion hinge strips

and similarly the toes of another lever 20 and another lever 21 are pivotally riveted to the adjacent ear 12 of the companion hinge member with their shanks inclined in the opposite direction and the ends of the shanks of the two pairs of levers 20, 21 are pivotally connected and the shanks of the two levers 21 are pivotally connected on an axis which will be in a plane midway between adjacent edges of the two members 10, 10 when they are in 60 the relation shown in Fig. 6.

By providing the bosses 16 the parts will assemble with adjacent ears 11 and 12 in the same plane so that a tongue 18 and a notch 17 will properly coact. Screw holes 25, in 65 the main strips 10 may also be formed symmetrically with relation to the ears 13 and 14 and yet be in alinement with the similar perforations of the companion plate when the parts are assembled, so that there will be no difficulty in pre-forming screw holes in the leaf sections preparatory to mounting the hinge.

When the hinge parts have been properly 70 assembled as shown, and secured to the leaf sections 26, 26, an unfolding of the leaf sections projects the two tongues 18 firmly into the adjacent notches 17 and, as the fastening screws 27 are placed close to the planes of the ears, the adjacent edges of the leaves 80 are brought into and held in a proper relation to each other.

I claim as my invention:

1. A hinge comprising two reversely arranged sheet metal strips of equal length, 85 the ends of which are upturned and perforated, the metal around the perforations of only one upturned portion of each strip being extended laterally of the portion, two pairs of levers pivotally associated with the adjacent upturned portion at the perforations thereof and pivotally connected with companion levers, said levers having thickness substantially equal to said lateral extensions, the intermediate portions of each of 90 said strips being provided with two perforations for the reception of fastening means, said perforations being symmetrically arranged relatively to the intermediate portion of the strip.

2. A hinge comprising two reversely arranged similar sheet metal strips of equal length, the ends of which are upturned and perforated, the material around the perforations of only one upturned portion of each strip extending laterally of the portion, and two pairs of levers pivotally associated with the adjacent upturned portions at the perforations thereof and pivotally connected with 10 companion levers, said levers having thickness substantially equal to said lateral extensions, the intermediate portions of each of said strips being provided with two perforations for the reception of fastening means, 15 said perforations being symmetrically arranged relative to the intermediate portions of the strips and the adjacent vertical edges of adjacent upturned portions being formed one with a notch and the other with a mating 20 tongue which interdigitate laterally of the hinge axis when the parts are moved to open position.

3. A hinge comprising two main body strips of equal length with upturned ears at 25 each end, two pairs of pivotally associated levers hingedly connecting said strips with the adjacent ears thereof in the same plane, one set of the levers being spaced from the upturned ends of one of said strips a distance 30 substantially equal to the thickness of one lever member, the adjacent vertical edges of adjacent strip ends having portions which interdigitate transversely and to one side of the axis of the hinge.

35 In witness whereof I, FREDERICK B. WALTER, have hereunto set my hand at Wabash, Indiana, this 25th day of July, A. D. one thousand nine hundred and twenty-eight.

40 FREDERICK B. WALTER.
